UNITED STATES PATENT OFFICE.

LOUIS A. SIEBERT AND CHARLES M. SIEBERT, JR., OF COLUMBUS, OHIO, ASSIGNEES TO THE SIEBERT-WELCH COMPANY, OF COLUMBUS, OHIO, A CORPORATION OF OHIO.

MASSAGE APPARATUS.

961,034.

Specification of Letters Patent. Patented June 7, 1910.

Application filed September 2, 1909. Serial No. 515,756.

To all whom it may concern:

Be it known that we, LOUIS A. SIEBERT and CHARLES M. SIEBERT, Jr., citizens of the United States, residing at Columbus, in 5 the county of Franklin and State of Ohio, have invented certain new and useful Improvements in Massage Apparatus, of which the following is a specification.

This invention relates to massage apparatus, the object of said invention being the provision of a massage device adapted for use in massaging internal portions of the body and one so constructed as to render possible the massaging of any given portion 15 of the internal passages of the human body without affecting the other portions of such passages.

Further objects and advantages of the invention will be set forth in the detailed description which now follows.

In the accompanying drawing: Figure 1 is a side elevation of a massage device constructed in accordance with the invention, Fig. 2 is a sectional view upon the line 25 $x-x$ of Fig. 1, and Fig. 3 is a sectional view upon line $y-y$ of Fig. 2.

Like numerals designate corresponding parts in all of the figures of the drawing.

The numeral 5 upon the drawing designates the tubular stem of a cup-like cap 6. This cap is threaded upon the neck 7 of a preferably hard rubber casing 8. The neck 7 is provided with an annular recess 9 into which a portion of a soft rubber bag 10 is 35 clamped by an annular rib 11, said rib being formed upon the cap 6.

One or more preferably elongated openings are formed in the wall of the casing 8 and the soft rubber bag protrudes through 40 these openings 12 when air or water under pressure is admitted to the interior of said bag through the stem 5, it being understood that said stem is to be connected by an ordinary rubber tube with any desired form of 45 massage machine in the usual manner.

It is apparent from the foregoing description that a rapid pulsation of the rubber bag through the opening or openings 12 may be secured by alternately admitting air

or water under pressure and releasing said 50 air or water through the stem 5. The same result may be achieved by creating alternate pressure and vacuum in the stem 5 by means of any of the well known forms of massage machines commonly employed for such purpose. 55

In use the casing 8 is inserted in the passage, the internal walls of which it is desired to massage. The pulsations of the rubber bag against the walls of the passage 60 through the openings or opening 12 results in stimulating and massaging the parts so treated and affords efficient means for massaging the interiors of the passages of the human body and also provides means for 65 localizing such treatment to whatever extent may be found desirable.

From the foregoing description it will be seen that simple and efficient means are herein provided for accomplishing the objects of the invention but while the elements herein shown and described are well adapted to serve the purposes for which they are intended, it is to be understood that the invention is not limited to the precise construction set forth, but includes within its purview such changes as may be made within the scope of the appended 70 claims. 75

Having described our invention what we 80 claim is:—

1. In a massage device the combination with a casing adapted to be inserted within the body, of a flexible lining within said casing adapted to protrude through an 85 opening formed in the wall of said casing and means for conducting pressure fluid to the interior of said flexible lining.

2. In a massage device the combination with a casing adapted to be inserted within 90 the body and having openings formed in the side walls thereof, of a flexible bag located within said casing and means for admitting pressure fluid to the interior of said bag.

3. In a massage apparatus the combination with an elongated casing adapted to be 95 inserted within the body, of a flexible bag

located within said casing, a cap threaded upon said casing, the edge of said bag being clamped between said cap and said casing and a stem carried by said cap through 5 which fluid pressure is admitted to the interior of said bag, said casing having an elongated opening formed in the side wall thereof.

In testimony whereof we affix our signatures in presence of two witnesses.

LOUIS A. SIEBERT.
CHARLES M. SIEBERT, JR.
